UNITED STATES PATENT OFFICE.

FORREST E. RICKETTS, OF CATONSVILLE, MARYLAND.

ELECTRICAL PROTECTIVE DEVICE.

Application filed September 24, 1920. Serial No. 412,546.

To all whom it may concern:

Be it known that I, FORREST E. RICKETTS, a citizen of the United States, and a resident of Catonsville, in the county of Baltimore and State of Maryland, have invented a new and useful Improvement in Electrical Protective Devices, of which the following is a specification.

My invention relates to electrical protective devices and particularly to means for protecting parallel-connected transmission circuits.

One object of my invention is to provide effective means for selectively protecting parallel-connected conductors.

Another object of my invention is to provide means for so decreasing the time elements of protective relays associated with faulty feeder circuits that the faulty circuits may be isolated before normal parallel-connected circuits become affected by the same fault.

Another object of my invention is to provide a system embodying means, of the above-indicated character, that shall require current-responsive relays only for controlling the protective devices.

A further object of my invention is to provide a system, of the above-indicated character wherein the necessity for progressive time elements may be obviated in the relays connected to successive sections of the system.

A still further object of my invention is to provide means for eliminating, under predetermined conditions, the time element that is normally maintained in a relay by a saturable torque-compensating transformer, by short-circuiting the transformer.

In a co-pending application, Serial No. 317,651, filed August 15, 1919, I disclose a selective balance relay that is employed for protecting parallel-connected transmission circuits in co-operation with the usual overload relay. The balance relay is energized through current transformers, from each of the parallel-connected circuits and is adapted to select either circuit, when a fault occurs therein, and to instantaneously trip the circuit interrupters of that circuit. Small pallet switches, that are actuated by the respective circuit interrupters, short-circuit the selective relay and the overload relay at the corresponding ends of the faulty circuit to prevent immediate actuation of the inter-

rupter in the normal circuit because of an unbalanced energization of the selective relay. The normal circuit remains in operation and retains its ordinary overload protection, with a predetermined time element in the operation of its relays, depending upon the value of the overload current.

United States Patent No. 1,286,239, issued Dec. 3, 1918, to A. W. Copley and B. H. Smith and assigned to the Westinghouse Electric & Manufacturing Company, discloses an induction-type protective relay embodying a torque regulator. The object of the torque regulator is to introduce a time element in the operation of the relay and to prevent, thereby, the instantaneous operation of the circuit interrupters upon the occurrence of a short-circuit or sudden heavy overload.

The torque regulator comprises an easily saturable current transformer connected between the circuit and the energizing winding of the relay. Beyond a certain value of circuit current, the current that traverses the secondary winding of the saturable transformer and the energizing winding of the relay remains substantially constant because of the saturation of the transformer. A time element is thus maintained irrespective of short-circuit currents of excessive values in the main circuit.

In the distributing systems heretofore employed, progressive time elements have been required in the relays employed in successive sections for protecting the apparatus connected to the system. In many instances, the progressive settings have necessitated an extremely large time setting in the relays at the generating station.

As stated above, one of the objects of the present invention is to obviate the necessity for the progressive time elements.

In distributing systems, instantaneous actuation of circuit interrupters on a faulty circuit is not desirable. I, therefore, employ the differential relay, that is disclosed in my co-pending application, in co-operation with the time-element protective relays, that are disclosed in the above-mentioned patent, to provide effective means for selectively protecting parallel-connected conductors, by so decreasing the time elements of the relays associated with the faulty conductors, as to effect the isolation thereof before the normal conductors become affected.

In practicing my invention, I provide protective relays that embody the torque regulator for protecting the parallel-connected circuits. The differential relay is so disposed that, upon an occurrence of a fault in either circuit, its contacts will select the relay or relays that protect the faulty circuit. I provide, further, an auxiliary switch or relay, the setting of which may be so adjusted that it will be actuated only when the circuit current attains a predetermined value. This relay, when actuated by the current of predetermined value, co-operates with the contact members of the differential, or selective, relay to short-circuit the torque regulator of the overload relay that is connected to the faulty circuit. The time element that is normally maintained by the torque regulator of the overload protective relay is thus decreased to about one-half the predetermined normal value.

The employment of the auxiliary switch, or relay, obviates the necessity for the additional pallet switch on the circuit interrupter and, since it may be disposed adjacent the differential or selective relay, effects considerable saving in wire which would, otherwise, be required for the connections between the pallet switch on the circuit interrupter and the terminals of the differential relay.

The use of the auxiliary relay, in combination with the differential relay also precludes the actuation of the differential relay upon the occurrence of surges in the circuit and also obviates the necessity for providing an exact balance in the current-transformer circuits. The differential relay may thus be made extremely sensitive without the disadvantages of requiring exact balances in the current transformers and of operating upon the occurrences of surges in the circuits.

The actual isolation of a circuit is thus made dependent upon the current in that circuit attaining a predetermined value and maintaining that value for a predetermined interval of time. The reduction of the interval of time required to isolate the faulty circuit, below the value of time required for the actuation of the circuit interrupters in the normal circuit, insures isolation of the faulty circuit only. With this arrangement, only relays that are responsive to current are necessary, and the expense incidental to supplying a plurality of potential transformers is obviated.

In the accompanying drawings,

Figures 1, 3 and 4 are diagrammatic views of electrical distributing systems embodying my invention; and

Fig. 2 is a diagrammatic view of a selective relay system embodying my invention.

Generator bus bars 1 and 2 are connected to substation bus bars 3 and 4 through two

parallel-connected feeder circuits 5 and 6. Circuit interrupters 7 and 8 are connected in the conductors 9 and 10, of the circuit 5, at the respective ends thereof. Circuit interrupters 11 and 12 are connected in conductors 13 and 14, of the circuit 6, at the respective ends thereof. Series transformers 15 and 16 are so disposed with respect to the circuit 5 as to have current induced therein that shall be proportional to the current traversing the two ends of the circuit 5. Similarly, transformers 17 and 18 are connected at the respective ends of the circuit 6. The transformers 15 and 17 are connected by an auxiliary circuit 19, and the transformers 16 and 18 are connected by an auxiliary circuit 20.

Time-limit overload relays 21 and 22, constructed substantially as indicated in the patent referred to above, are connected to the transformers 15 and 17, respectively, for the purpose of controlling the tripping magnets 23 and 24 of the interrupters 7 and 11, respectively. The relays 25 and 26 are similarly connected to the current transformers 16 and 18 for the purpose of controlling the tripping magnets 27 and 28 of the interrupters 8 and 12, respectively. The overload relays 21, 22, 25 and 26 are adapted to complete the circuits through the respective tripping magnets controlled thereby, from auxiliary circuits 70 and 80, respectively.

The time-limit overload relays 21, 22, 25 and 26 severally comprise a current transformer 29 having a primary winding 29 and a secondary winding 30, a torque regulating saturable transformer 31 and a winding 32 which co-operates with the winding 30 to operate the relay.

The primary winding 29 of each relay is energized from the corresponding current transformer. The energization of the winding 32 is controlled by the saturable transformer 31 which comprises a primary winding 33 and a secondary winding 34. The primary winding 33 is energized directly in accordance with the value of the current that traverses the circuit 5 or the circuit 6 but the current induced in the secondary winding 34 is substantially constant because of the saturation of the regulating transformer 31 which is connected between the winding 30 and the winding 32.

When the winding 32 is sufficiently energized for a predetermined interval of time, engagement is effected between the contact members 35 and 35' of the relay.

A differential or selective relay 36 is employed with each set of overload relays at the respective ends of the parallel-connected conductors. The selective relay 36 comprises two windings 37 and 38, that are energized from the current transformers of the parallel-connected conductors, and a third winding 39 that is connected between the

junctures of the current transformer windings and of the windings 37 and 38 of the relay 36. The relay 36 further comprises a movable contact member 40 that is adapted 6 to engage either of two stationary contact members 41 and 42, depending upon the respective degree of energization of the windings 37 and 38.

Two auxiliary relays 43 and 44 are employed to co-operate with the contact members of the relay 36 to short-circuit the torque regulators 31 in the overload relays 21 and 22. Similarly, a differential relay 45 and two auxiliary relays 46 and 47 operate to short-circuit the torque regulators of the relays 25 and 26. As the torque regulator is short-circuited, the winding 32 is energized in direct accordance with the value of the current traversing the circuit and the time element, that is normally maintained by the torque regulator, is eliminated.

One terminal of the secondary winding of the current transformer 15 is connected to one terminal of the winding 29, of the relay 21, and the winding 48 of the auxiliary switch 43 is connected between the second terminal of the winding 29 and the free terminal of the winding 37 of the relay 36. The winding 49, of the auxiliary switch 44, is similarly connected between the free terminal of the winding 38, of the selective relay 36, and one terminal of the winding 29 of the relay 22, the other terminal of winding 29 being connected to one terminal of the transformer 17. The other terminals of the current transformers 15 and 17 are both connected to the free terminal of the winding 39 of the selective relay 36.

A terminal of the primary winding 33 and 40 a terminal of the secondary winding 34 of the torque regulator 31 are joined by a conductor 50. The other terminal of the winding 33, of the relay 21, is connected to a contact member 51, of the auxiliary relay 48, 45 and the other terminal of the winding 34, of the relay 31, is connected to the contact member 41 of the selective relay 36. The contact members 52, of the auxiliary relays 43 and 44, are both connected to the movable contact member 40 of the selective relay 36. Similarly, one terminal of the winding 33, of the relay 22, is connected to terminal 51, of the auxiliary relay 44, and one terminal of winding 34 of the relay 22 is connected 55 to the stationary contact member 42 of the selective relay 36.

The windings of the relays 25, 26, 45, 46 and 47 are similarly connected, through the current transformers 16 and 18, to the circuits 5 and 6.

In a system employing an even number of circuits to distribute energy, the circuits may readily be grouped in pairs with a selective relay for each pair of circuits, at the respective ends thereof. In a system having an

odd number of circuits, the circuits are grouped in pairs, and the odd circuit may be provided with ordinary overload protection, as is illustrated in Figs. 1 and 3.

In Fig. 1, the odd circuit 53 is provided with circuit interrupters 54 and 55 at the respective ends thereof. Current transformers 56 and 57 and overload relays 58 and 59 are provided at corresponding ends of the circuit 53 for the purpose of controlling the 70 tripping magnets 60 and 61 of the interrupters 54 and 55, respectively. The overload relays 58 and 59 are adapted to complete the circuits through the corresponding tripping magnets 60 and 61 controlled thereby, from 75 the auxiliary circuits 70 and 80, respectively.

The time interval of each of the overload relays 21, 22 and 58, since they are adjacent the generator end of the circuits 5, 6 and 53, 80 may be, for convenience, two seconds. The relays 25, 26 and 59 should, however, be adjusted for a smaller time interval and, for convenience, may be considered as having a time interval of one second each.

Similarly, such relays as might be disposed in successive sections, as illustrated in Figs. 3 and 4, for the protection of parallel-connected feeder circuits connected therein, would have corresponding time intervals of 85 two seconds for the relays adjacent the power end of the circuits and of one second for the relays adjacent the load end of the circuits.

A system having only two parallel-connected feeder circuits between the generator 100 62 and the substation bus-bars 63 may be provided with the differential relay protective system at each end of the feeder circuits if an additional source of energy 64 is available at the substation, as in Fig. 4. 105 Where, however, no additional source of energy is available, a third feeder circuit should be provided to obtain a greater degree of protection, as in Fig. 1 or in the section shown in Fig. 3 between the first and 110 second substation bus-bars 63 and 65, respectively.

If in Fig. 1 a fault should occur at the point X in the circuit 5, a current of greater value would traverse the current transformer 15 than the transformer 17 and the winding 37 of the selective relay 36 would be energized to a greater degree than the winding 38. Engagement would thereupon be effected between the contact members 40 and 41.

When the value of the current traversing the transformer 15 attains a predetermined value, the auxiliary relay 43 operates to effect engagement between its contact members 51 and 52. A circuit is then completed from one terminal of the winding 33 in the relay 21 through the contact members 51 and 52 of the auxiliary relay 43 and the contact members 40 and 41 of the selective relay 36.

to the corresponding terminal of the winding 34 of the torque compensator 31 in the relay 21, thereby completely short-circuiting the torque compensator 31 and permitting 5 the winding 30 to directly energize the winding 32. The time element normally maintained by the torque compensator 31 would thus be eliminated and engagement of the contact members 35 and 35^a would be effected 10 to energize the tripping magnet 23 of the interrupter 7 before the relay 22 could similarly energize the tripping magnet of the interrupter 11.

The circuit interrupter 8 would similarly 15 be tripped, through the action of its relay 25 and the differential relay 45, before the interrupter 12 could be actuated, and the circuit 5 would be completely isolated.

The normal circuit 6 would continue in 20 operation and, although the energization of the winding 38 of the differential relays 36 and 45 would effect engagement between the contact members 40 and 42, the overload relays 22 and 26 would continue to operate 25 normally because the setting of the auxiliary relays 44 and 47 would preclude the operation thereof until the current traversing the circuit 6 attained a predetermined value. The employment of the auxiliary switches 30 43 and 44 also precludes tripping of circuit interrupters upon the occurrence of surges in the circuits.

The desired time element in the overload 35 relays is thus normally maintained for ordinary overload protection. The employment of the differential relay to short-circuit the compensators of the relays connected to a circuit wherein a fault occurs, serves to decrease the time element sufficiently to permit 40 isolation of the faulty circuit before the interrupters of the parallel-connected circuit may be tripped.

My invention is not limited to the specific 45 arrangement illustrated, as it may be variously modified without departing from the spirit and scope of the invention as set forth in the appended claims.

I claim as my invention:

1. In an electrical system of distribution, 50 the combination with parallel-connected feeder conductors, of means having a time element and responsive to the current traversing the conductors and means for reducing the time element of the current responsive means comprising means responsive to an unbalance in the current traversing the parallel conductors.

2. In an electrical system of distribution, 60 the combination with parallel-connected feeder conductors, of means having a time element and responsive to the current traversing the conductors, means responsive to an unbalance in the current traversing the parallel conductors for reducing the time element of the current responsive means, and

means responsive to a predetermined value of current in the conductors for rendering the unbalance-responsive means operative.

3. In an electrical system of distribution, 70 the combination with parallel-connected feeder conductors, of means having a time element and responsive to the current traversing the conductors and means responsive to an unbalance in the current traversing the parallel conductors for reducing the time 75 element of the current-responsive means of only the circuit that is so affected as to cause an unbalance in the current relations of the parallel-connected feeder conductors.

4. In an electrical system of distribution, 80 the combination with parallel-connected feeder conductors, of means having a time element and responsive to the current traversing the conductors and a relay operative 85 only when the currents traversing the conductors are unbalanced for reducing the time elements of the current-responsive means of only the circuit that is so affected as to cause an unbalance in the current relations 90 of the parallel-connected feeder conductors.

5. In an electrical distribution system, the combination with a plurality of parallel-connected feeder conductors extending between two points of the system, of relays having a predetermined time element for disconnecting the conductors from the system, and relay controlling means for selecting and rendering the disconnecting relays of faulty feeder conductors operative and for simultaneously decreasing the predetermined time element to disconnect the faulty conductors before the normal parallel-connected conductors become disconnected from the system. 95

6. In an electrical distribution system, the combination with a plurality of parallel-connected feeder conductors extending between two points of the system, of relays having a predetermined time element for disconnecting the conductors from the system, and selective means for decreasing the predetermined time element of the relay associated with a faulty feeder to disconnect the faulty conductors before the normal parallel-connected conductors become disconnected from the system. 105

7. In an electrical distribution system, the combination with a plurality of parallel-connected feeder conductors extending between two points of the system, of relays having a predetermined time element for disconnecting the conductors from the system upon occurrences of overload or short-circuits on the feeder conductors, and selective means for rendering the disconnecting relays of a faulty feeder operative only upon the occurrence of a short-circuit thereon and for simultaneously decreasing the predetermined time element to disconnect the faulty conductors before the normal parallel-con- 110 115 120 125 130

nected conductors become disconnected from the system.

8. In an electrical distribution system, the combination with a plurality of parallel-connected feeder conductors extending between two points of the system, of relays having a predetermined time element for disconnecting the conductors from the system, and relay-controlling means for selecting the disconnecting relays of faulty feeder conductors and simultaneously decreasing the predetermined time element to disconnect the faulty conductors before the normal parallel-connected conductors become disconnected from the system.

10. In an electrical distribution system, the combination with a plurality of parallel-connected feeder conductors extending between two points of the system, of relays having a predetermined time element for disconnecting the conductors from the system, relay-controlling means for selecting the disconnecting relays of the faulty feeder conductors, and means responsive to a predetermined value of current in the faulty feeder for decreasing the predetermined time element to disconnect the faulty conductors before the normal parallel-connected conductors become disconnected from the system.

11. In an electrical distribution system, the combination with a plurality of parallel-connected feeder conductors extending between two points of the system, of relays having a predetermined time element for disconnecting the conductors from the system, and means for decreasing the time element of the corresponding disconnecting relays to obtain a quick disconnection of a faulty feeder conductor.

12. In an electrical distribution system, the combination with a plurality of parallel-connected feeder conductors extending between two points of the system, of relays having a predetermined time element for disconnecting the conductors from the system, a current transformer in each conductor for energizing the disconnecting relays, and means for selecting the corresponding relays of a faulty conductor and decreasing the predetermined time element thereof to disconnect the faulty conductors from the system before the normal parallel-connected conductors become disconnected from the system.

13. The combination with an induction relay and a torque regulating device for causing the time of operation thereof to be substantially constant, of means for neutralizing the effect of the torque regulating device.

65

14. The combination with an induction relay and a torque regulating device for causing the time of operation thereof to be substantially constant, of a relay for neutralizing the effect of the torque regulator.

70

15. The combination with an induction relay and means for causing the time of operation thereof to be substantially constant, of means responsive to the current traversing the relay for neutralizing the effect of the timing means.

16. The combination with an induction relay and means for causing the time of operation thereof to be substantially constant, of means responsive to a predetermined value of current traversing the relay for neutralizing the effect of the timing means.

80

17. The combination with an induction relay having means for controlling the time element thereof, of means for controlling the time-element controlling means in accordance with predetermined conditions.

85

18. The combination with a circuit and an induction relay connected thereto having means for controlling the time element thereof, of means for controlling the time-element controlling means in accordance with the current in said circuit.

90

19. In an overload relay, the combination with an actuating winding and a saturable transformer connected between the winding and the circuit to which the relay is connected, of means for short-circuiting the transformer under predetermined conditions.

100

20. The combination with a circuit and an induction relay connected thereto having normally a definite-time characteristic when current in excess of a predetermined value traverses said circuit, of means for altering said characteristic under predetermined conditions in the circuit.

105

21. The combination with two parallel transmission circuits and a relay having a predetermined time characteristic for controlling one of said circuits, of means including a balanced device controlled by the currents in said circuits for altering said characteristic when a fault occurs in said one of said circuits.

110

In testimony whereof, I have hereunto subscribed my name this eighteenth day of September 1920.

FORREST E. RICKETTS.
